UNITED STATES PATENT OFFICE.

CLINTON D. Tabor, of New Dorp, New York, assignor to Tabor Sash Company, of Newark, New Jersey, a corporation of New Jersey.

COMBINED SASH LOCK AND OPENER.

987,330.

Specification of Letters Patent. Patented Mar. 21, 1911.

Application filed April 23, 1908. Serial No. 428,754.

To all whom it may concern:

Be it known that I, CLINTON D. Tabor, a citizen of the United States, residing at New Dorp, in the county of Richmond and 5 State of New York, have invented a new and useful Improvement in Combined Sash Locks and Openers, of which the following is a specification.

This invention relates to opening and 10 locking means which are applicable more particularly to centrally pivoted sashes which are capable of both a horizontally swinging movement and also a vertically sliding movement in the frame.

15 The object of this invention is to provide simple and efficient means whereby these functions can be easily and reliably performed.

In the accompanying drawings consisting of 2 sheets: Figure 1 represents an inside elevation of a sash and frame provided with my improvements. Fig. 2 is a vertical section thereof in line 2—2, Fig. 1. Fig. 3 is a horizontal section in line 3—3, Fig. 1. 25 Fig. 4 is a fragmentary vertical section on an enlarged scale taken in line 4—4, Fig. 1, and showing the position of the sash opening and locking device when the sash is closed. Figs. 5, 6 and 7 are views similar to 30 Fig. 4 showing different positions of the sash opening and locking device. Figs. 8, 9 and 10 are perspective views showing the parts of the sash opening and locking device detached. Fig. 11 is a fragmentary 35 vertical section in line 11—11, Fig. 1.

Similar letters of reference indicate corresponding parts throughout the several views.

1 represents the window frame comprising 40 two upright side jambs 2, 3, a horizontal main sill 4 connecting the lower ends of the side jambs and a horizontal head jamb 5 connecting the upper ends of the side jambs.

6 represents the sash which is capable of 45 turning in a horizontal plane and also of sliding vertically in the frame. For this purpose the sash is pivoted centrally by its upper and lower rails 7, 8 by any suitable means. In the closed position of the sash 50 the same is in line with the frame and engages by means of an outwardly facing shoulder 9 on its outwardly closing stile 12 with an inwardly facing shoulder or stop 10 on the adjacent side jamb 2 of the frame 55 and by an inwardly facing shoulder 11 on

its inwardly closing stile 12^a with an outwardly facing shoulder or stop 13 on the adjacent side jamb 3 of the frame while its lower rail 8 rests upon a stool 14 secured to the upper side of the main sill. The space 60 between the top rail and the head jamb is closed by a follower or strip 15 which engages with its under side against the upper edge of the top rail while its upper edge is arranged in a pocket or a recess 16 formed 65 between inner and outer cleats, strips or bars 17, 17 secured to the underside of the head jamb. While in this closed position a weather tight joint is produced between the bottom rail and stool by means of a longitudinal rib 18 formed on the upper side of 70 the stool and engaging with a longitudinal groove 19 on the underside of the bottom rail and the joint between the top rail and the follower is also rendered weather tight 75 by means of a longitudinal rib 21 formed on the underside of the follower and engaging with a longitudinal groove 20 in the upper side of the top rail, as shown in Fig. 11.

The pivotal connection between the lower 80 rail of the sash and the stool comprises a sill plate 22 secured centrally to the upper side of the stool and provided with an upwardly projecting pivot pin 23 which enters a socket formed partly in a lower sash plate 85 24 which is secured centrally to the underside of the lower rail and partly in said rail above the plate 22.

The pivotal connection between the upper 90 or top rail of the sash, the follower and the head jamb consists of a vertical pin 25 secured at its upper end to the head jamb and arranged with its lower part in a central opening 26 in the follower and a socket 27 95 in the top rail and also through coinciding openings 28, 29 formed in pivot plates 30, 31 which are secured respectively to the upper side of the top rail and the underside of the follower, as shown in Fig. 2.

The follower is yieldingly held in its depressed position in engagement with the top rail of the sash by a spring 36 surrounding the upper pivot pin 25 and bearing at its upper end against the base of said pin while its lower end bears against the upperside of 100 the follower plate 31.

Upon turning the sash from its closed and lowered position the wedge action of the ribs and grooves between the lower end of the sash and the frame causes the sash to be 110

lifted until the lower rail of the sash reaches the top of the lower ribs after which it rests on top of these ribs and remains in this vertical position upon swinging the sash 5 horizontally into a more or less open position. While thus raising and turning the sash the follower rises with it and is raised an additional extent by the wedge action of the coöperating upper ribs and grooves between these parts. Upon swinging the sash back into its closed position into line with the frame the sash drops with its lower groove over the rib on the stool and the follower descends with its rib into engagement 10 with the groove of the head rail.

My improved means for opening the sash and locking the same in its closed position are constructed as follows:—37 represents an upright locking plate secured to the face of the jamb 2 by screws or otherwise and provided with a forwardly projecting locking lug 38. The latter is provided at its front end with an upwardly projecting lip 39 forming an outwardly facing shoulder 40 while its inner end is curved or rounded downwardly and outwardly to a downwardly facing shoulder 41 on the underside of this lug.

42 represents a pivot plate secured to the edge of the sash stile 12 and provided with an inwardly projecting pivot lug 43 which carries a pivot pin or stud 44 projecting laterally toward the adjacent side jamb 2 of the frame. Upon this stud is pivoted the upper 30 end of a vertically swinging handle or hand lever 45 which has its lower end constructed in the form of a hook-shaped finger piece for convenience in taking hold of the same with a finger. Below its pivot this handle is provided with an upwardly facing shoulder 47 which is adapted to engage with the downwardly facing shoulder 41 of the locking lug 38 on the frame. Projecting inwardly and downwardly from the handle adjacent to its 40 pivot is a locking dog 46 which is adapted to engage with the inwardly facing shoulder at its front end with the outwardly facing shoulder on the upper side of the locking lug 40. Above its pivot the handle is provided 45 with a heel or tail piece 48 which is arranged at an angle to the handle and adapted to engage with the adjacent part of the locking lug plate or other stationary part on the frame.

55 While the sash is swung into its closed and lowered position and the opening and locking device is in its operative position the handle is arranged vertically and engages with its upwardly facing shoulder against 60 the downwardly facing shoulder on the underside of the locking lug, the locking dog engages its end with the rearwardly facing shoulder of the locking lug and the heel is separated from the frame, as shown in Fig. 4. In this position of the parts it is impos-

sible to raise the sash owing to the engagement of the handle shoulder with the underside of the locking lug and it is also impossible to turn the sash horizontally owing to the engagement of the dog with the outwardly facing shoulder of the locking lug. It is therefore impossible to open the sash from the outside of the building and it is also impossible to open the sash from the inside of the room except by manipulating the opening and locking device. When it is desired to open the sash, the hand lever is first swung inwardly and upwardly until its locking dog clears the outwardly facing shoulder of the locking lug and the heel thereof bears against the adjacent part of the sash or locking plate, as shown in Fig. 5, and upon then continuing this upward and inward movement of the handle and sash is simultaneously raised and its swinging side is moved inwardly, during which movement the upwardly facing shoulder of the handle swings inwardly and upwardly around the curved face of the locking lug and clears the same so that the sash can be swung wide open. As the tail of the hand lever engages the frame during this inward and upward movement of the handle a lifting effect is produced on the sash which relieves the wedge action of the coöperating inclined surfaces of the rib and groove on the stool and the bottom rail, thereby causing these parts to wear less and the sash to be opened more readily and easily.

When the sash has been fully opened and the handle is released the parts of the opening and locking device assume the relative position, shown in Fig. 6. Upon subsequently turning the sash in the direction for closing the same the parts of the locking device remain in this position until the sash has nearly completed its closing movement at which time the locking dog engages with its underside against the top of the locking lip, as shown in Fig. 7. As the sash completes its horizontal closing movement and drops into its lowered position the locking dog is lifted by the lip together with the handle and when the dog has cleared this lip it drops into engagement with the shoulder on the outer side of this lip and the handle swings with its lower shoulder around the curved end of the locking lug and into engagement with the shoulder on the underside thereof, as shown in Fig. 4, whereby the sash is again locked against upward and inward movement. This operation of locking the sash is wholly automatic and effected solely by swinging the sash into its closed position in line with the frame, thereby dispensing with separate closing and locking operations for this purpose. By thus combining the sash opening and locking device in one structure the fittings which ordinarily would be required for this purpose

pose on a window of this character are materially reduced and the appearance of the same is much improved.

I claim as my invention:

5 1. A lock and opener for a sash pivoted on a frame, comprising a lug adapted to be secured to the frame, and a handle adapted to be pivoted on the sash and provided with bearing surfaces adapted to engage with 10 opposite sides of said lug and with a heel adapted to engage with the frame.

15 2. A lock and opener for a sash which is capable of swinging horizontally and also sliding vertically in a frame, comprising a lug arranged on the frame, and a handle pivoted on the sash to swing vertically thereon and having a shoulder adapted to engage with the underside of said lug, a finger adapted to engage with the upper side of 20 said lug and a heel adapted to engage with the frame.

25 3. A lock and opener for a sash which is capable of swinging horizontally and also sliding vertically in a frame, comprising a lug arranged on the frame, and having its underside curved inwardly and upwardly and its upper side provided with a lip forming an outwardly facing upper shoulder, and a handle pivoted at its upper end on the sash 30 to swing vertically and provided with an

upwardly facing shoulder adapted to engage with the underside of said lug, a downwardly and inwardly inclined dog adapted to engage with said outwardly facing shoulder and an upwardly projecting heel adapted to engage with the frame. 35

4. A lock and opener for a sash which is capable of swinging horizontally and also sliding vertically in a frame, comprising a frame plate secured to the frame and having 40 an inwardly projecting locking lug which has an outwardly facing shoulder on its upper side and a rounded underside, a sash plate adapted to be secured to the sash and provided with an inwardly projecting pivot 45 lug, and a hand lever pivoted at its upper end on said pivot lug to swing vertically and provided with an upwardly facing shoulder adapted to engage with the underside of said locking lug, an inwardly and downwardly 50 inclined dog adapted to engage with the outwardly facing shoulder of the locking lug, and an upwardly projecting heel adapted to engage with the frame plate.

Witness my hand this 20th day of April, 55
1908.
